UNITED STATES PATENT OFFICE.

WILLIAM C. JOHNSON, OF MCKEESPORT, PENNSYLVANIA.

FLANGE-LUBRICATING DEVICE.

1,276,538.

Specification of Letters Patent. Patented Aug. 20, 1918.

Application filed February 24, 1917. Serial No. 150,706.

To all whom it may concern:

Be it known that I, WILLIAM C. JOHNSON, a citizen of the United States, residing at McKeesport, in the county of Allegheny and State of Pennsylvania, have invented 5 certain new and useful Improvements in Flange-Lubricating Devices, of which the following is a specification.

This invention relates to new and useful 10 improvements in flange lubricating devices.

This device belongs to the type of lubricators designed for dispensing a suitable lubricant upon the contact or working flange of a wheel adapted for operation upon a 15 track whereby the passage of the wheel over a curved track is greatly facilitated, the present device being especially efficient upon engines working upon short curves.

The device also provides facilities for 20 varied and accurate adjustment of a lubricant dispenser operatively arranged for use upon a flange wheel, the same including a serviceable pivot connection maintaining a lateral pressure of the device upon the wheel, 25 adjustable limiting means being arranged for controlling the same.

The device is further designed to provide 30 an enlarged area of dispensed lubricant bearing upon a wheel flange and governed by the height of the flange and the condition of the track, the device being of compact arrangement with a large holding capacity for the lubricant to be dispensed thereby.

It is also the object of the device to provide 35 a feeding mount for the lubricator whereby the contact dispensing portion of the latter is resiliently maintained in operative contact with a wheel flange until the same is entirely worn away during the operation of the device. The present construction 40 provides a lubricant dispensing tube constantly held against the flange of the wheel by resilient means allowing the same to follow all of the movements of the wheel 45 while the lubricant is prevented from spreading over the tread of the wheel. In the drawings forming a part of this application in which like designating characters refer to corresponding parts throughout the 50 several views.

Figure 1 is a view partly in elevation, partly broken away and in longitudinal section,

Fig. 2 is a top plan view thereof.

Fig. 3 is a sectional view taken upon line 55 III—III of Fig. 2 in the direction indicated by the arrows.

Fig. 4 is a rear end elevational view of the dispensing member.

Fig. 5 is a side view of a portion of a 60 wheel showing the contact 2 operatively positioned thereon.

Fig. 6 is a side elevational view thereof partially broken away taken on a reduced scale. 65

Fig. 7 is a transverse sectional view through the container.

Fig. 8 is a longitudinal sectional view through a contact tube of the form illustrated in Fig. 10. 70

Fig. 9 is a forward end elevational view thereof.

Fig. 10 is a central longitudinal sectional view through another form of the device and the adjustable mounting means therefor. 75

Fig. 11 is a front view of the same, and

Fig. 12 is an elevational view of the complete device in its operative position.

Referring more in detail to the drawings it is first noted that the device broadly consists of a lubricant dispenser 10 and a positioning bracket or support 11, the form of the device illustrated in Fig. 1 providing a dispenser in all essentials the same as that set forth in my Patent No. 1, 186,001, dated June 6, 1916, the difference existing being the arrangement of a single piece container 12 instead of the two piece construction of my said patent, a different form and arrangement of contact tube 13 being provided as well as the mounting means for the device consisting of the said bracket 11. 80 85 90

It will be understood that the dispenser 10 consists of a tubular container 12 elliptical in cross section as illustrated in Fig. 7 95 of the drawing, an ejecting piston 14 being operatively arranged within the lubricant receiving chamber 15 of the container, the resilient feeding of the piston being regulated by the tensioning means 16 as set forth in my above named patent.

The feeding bracket 11 comprises a post 17 having a tubular arm 18 perpendicularly projecting through the head 20 of the said post 17. A U-shaped flange 21 is provided 100 upon one side of the container tube 12 to

which the post 17 is adjustably secured at its lower end by means of a suitable bolt 22.

A sleeve 23 is arranged through which the arm 18 is slidably positioned, while a helical feed spring 24 surrounding the arm 18 being tensioned between the post head 20 and an adjusting nut 25 is adjustably threaded upon the sleeve 23. Relative rotation between the sleeve 23 and arm 18 is prevented by means of a key 26 slidably arranged through slots 27 in the diametrically opposite sides of the said arm, the said key also extending through the opposite sides of the sleeve 23 being removably retained in such arrangement by cotter pins 28, it being understood that the arm 18 is normally prevented from being withdrawn from the sleeve 23 by means of the said key 26 while separation of said elements may be effected upon removing the key.

A swivel head 29 forms a portion of the bracket 11 for connecting the sleeve 23 with a stationary bar 30 fixed to the vehicle frame. A journaling member or axle 31 radially projects from the sleeve 23 upon which a collar 32 is journaled, a short tube 33 being carried by the said collar extending perpendicularly with respect thereto and adapted for slidably mounting upon the bar 30, the same being secured in its adjusted position thereon by means of set screws 34. An annular flange 35 is provided upon the axle 31 spaced from the sleeve 23 forming an end stop for the inner side of the collar 32 while an adjustable stop or cap 36 is arranged for the other end of the collar 32 being adjustably positioned upon the reduced end 37 of the axle 31 and being either journaled or threaded thereon as desired, the same being herein illustrated in threaded engagement therewith. A coil spring 38 encircles the axle 32 having one end thereof seated in a desirable one of several sockets 39 arranged in the said axle, while the opposite end of the spring is positioned within a slot 40 in the outer edge of the collar 32 being retained therein by the said cap 36 positioned to overlie the same. When the cap 36 is in its seated position within the end of the collar 32, the same forms a journal member for the collar and is locked in position upon the axle portion 37 by a nut 41 while the movement of the collar 32 upon the said axle is limited by means of a radially projecting stop lug 42 arranged at the outer side of the tube 33 for engagement by a lever 43 radially carried by the cap 36.

It will be understood that with the spring 38 positioned with its opposite ends in one of the sockets 39 and notch 40, the collar 32 may be revolved upon the axle 31 when the cap 36 is released, and when the tension of the spring 38 is sufficiently strong the cap 36 is moved inwardly and locked in position upon the extension 37 by the nut 41 where-

by the spring 38 will resiliently maintain the lever 43 normally in contact with the lug 42. The tension of the spring 38 is such as to tend to lower the post 17 and tilt the forward end of the dispenser downwardly, it being understood that pressure exerted upon the forward end of the dispenser tilts the post 17 upwardly and further tensions the spring 38 and removes the lever 43 away from the lug 42, the elements having the tendency to return the lever 43 forwardly in contact with the said lug.

The contact tube 13 is removably secured in any desired manner within the forward flange 44 of the container 12 as by means of opposite bolts 45 secured through U-shaped side lugs 46 and 47 carried respectively by the contact tube 13 and the container 12. The cross sectional area of the tube 13 is greater than that of the container 12, it being understood that when the forward open end face 47 of the contact tube 13 is pressed against the wheel flange as 48, the lubricant as 49 will spread out within the tube 13 entirely filling the same and presenting a broad contact surface for engaging the wheel.

The complete operation of the device will be apparent as the contact tube face 47 is positioned upon the wheel engaging the tread thereof as best illustrated in Figs. 5 and 6 of the drawings the same being accomplished by forcing rearwardly the arm 18 and compressing the spring 24. The spring 24 thereupon feeds the entire dispenser 10 forwardly with the tube 13 in contact with the wheel compensating for wearing away of the contact tube, the length of travel of the arm 18 permitted by the key 26 being sufficient to feed the dispenser 10 forwardly until contact tube 13 is substantially worn out. The spring 38 allows the dispenser 10 to be forcibly tilted above the wheel, the same automatically returning to its operative position upon being released, the action of the spring 38 being limited by the lug 42 when contacted by the arm 43. The contact tube 47 is provided with oppositely extending base flanges 50 adapted to receive any overflow of the lubricant and preventing the same from covering the tread such as 51 of the wheel 52 for the lubrication of the flange 48 for which the device is arranged.

In Figs. 10, 11, and 12 of the drawings I have illustrated the lubricator identically with that set forth in Fig. 5 of my former Patent No. 1,186,001 and herein referred to with the exception that the contact tube 53 is rigidly secured to the container 54, the entire dispenser 55 including the said container and contact tube being shiftably mounted directly upon a mounting bar 30 by means of a swivel head 56 similar to the head 29 heretofore described. An expelling piston is arranged within the container 51.

for projecting the lubricant from the chamber 58 therein to and through the contact tube 53 having an enlarged opening 59.

The head 56 is provided with an axle 31' 5 radially projecting from a sleeve 23' through which the container 54 is slidably positioned. A feed spring 24' is tensioned between a lock nut 60 provided upon the container 54 for the contact tube 53 and an adjustable 10 nut 25' threaded upon the sleeve 23'. A collar 32' is journaled upon the axle 31' bearing a tube 33' carried thereby and secured to the bar 30' by screws 34'. The remaining elements of the swivel 56 as well 15 as the operation thereof are identical to those of the swivel head 29 and need not be again described, it being noted that the cap 36' is freely positioned upon the extension 37' of the axle 31'. The contact tube 53 has 20 laterally projecting side flanges 50'.

This form of mount for the lubricator is especially serviceable for mounting upon spring supported members such as the rail 58' of a car body, the dispenser 55 being operatively arranged with respect to the flange 48' of a wheel 52' as illustrated in Fig. 12 thereof, the tube 54 being fed forwardly by the spring 24' with the contact tube 53 in engagement with the wheel while the spring 38' of the swivel head 56 tends to swing the contact tube toward the wheel. A serviceable device is arranged which affords a large area for the lubricant being dispensed and the same may be mounted either rigidly 35 with the wheel traveling means, or upon the spring carried frame of the vehicle. The arrangement is such that the contact tube is maintained operatively against the wheel during all varying traffic conditions.

40 It will be understood that the present dispenser is adapted for employing both soft and hard lubricants, being especially adapted for dispensing the jelly like form of lubricant which readily fills the enlarged feed 45 member when projected therein by the piston of the dispenser, its action being by reason of the retarded outflow of the lubricant by reason of its operative engagement with the wheel being operated upon. It will 50 be noted that the feed members herein shown are slightly arcuate in form for adapting the bearing end thereof to the periphery of a wheel, the lubricant collecting base flanges of the feed members being arranged upon 55 the same arc as the adjacent side of the feed member for permitting the forward ends of the said flanges to conform to the curvature of the wheel. A lubricant spray may be employed within the feed member if desired.

60 What I claim as new is:

1. In combination with a lubricant dispensing tube and a supporting means therefor, a bracket rigidly attached to said dispensing tube and slidably connected to said

supporting means, and means associated with said bracket to yieldably forwardly slide said dispensing tube and bracket relatively to said supporting means in feeding contact to the wheel flange.

70

2. In combination with a lubricant dispensing tube, a bracket attached thereto, a tensioned forward feeding means for the bracket whereby the dispensing tube is bodily resiliently operatively mounted in 75 feeding contact with the wheel flange and a resilient swivel mount for the said feeding means.

75

3. In combination with a lubricator for wheel flanges having a dispensing tube, a resilient longitudinal shifting means for said distributing tube and a normally operative tensioned spring rotating head for the said shifting means.

80

4. A device of the class described comprising in combination with a lubricant dispenser having a dispensing tube, a bracket secured to said tube, an arm carried by the said bracket, a sleeve adjustably fixed to said arm, and a movement imparting spring 85 for the arm and dispensing tube positioned between the said sleeve and bracket.

85

5. A device of the class described comprising in combination with a lubricant dispenser having a dispensing tube, a bracket secured to said tube, an arm carried by the said bracket, a sleeve adjustably fixed to said arm, a movement imparting spring for the arm and dispensing tube positioned between the said sleeve and bracket, a mounting tube 90 and a spring swivel head between the said tube and sleeve.

90

6. In combination with a lubricant dispenser having a dispensing tube, a bracket detachably connected to said tube, a tubular arm projecting from said bracket having slots formed in the opposite sides thereof, a sleeve slidably mounted upon said arm, a key carried by said sleeve projecting through the said slots and a regulable feed spring 105 positioned between the said sleeve and bracket.

100

7. In combination with a lubricant dispenser having a dispensing tube, a bracket detachably connected to said tube, a tubular arm projecting from said bracket having slots formed in the opposite sides thereof, a sleeve slidably mounted upon said arm, a key carried by said sleeve projecting through the said slots, a regulable feed spring 115 slidably mounted between the said sleeve and bracket, a swivel head carried by said sleeve adapted for imparting partial rotation thereto and a mounting perpendicularly arranged upon the said head.

115

8. The combination with a dispensing tube of a lubricant dispenser for wheel flanges, of means for imparting longitudinal sliding and limiting rotary movements to said dispensing tube whereby the latter is resiliently 120

125

130

maintained in operative engagement with the wheel flange.

9. The combination with a lubricant dispenser having a dispensing tube, of a swivel head comprising an axle for slidably supporting the lubricant dispenser, a collar journaled upon said axle, a spring encircling the axle and adjustably connecting the collar and axle, a mounting tube carried by the collar, a lug upon the tube and a cap adjustably carried by the collar, having a lever adapted for engagement with the said lug when the spring is under tension.

10. In combination with a lubricant dispensing tube for wheel flanges, a mounting tube therefor, connecting means between the said mounting tube and dispenser, tensioned rotation imparting means for the dispenser carried by said connector and adjustable limiting means for said rotation imparting means whereby the dispenser is free to move outwardly of the wheel being operated upon and to a limited extent in a direction toward the axis of the wheel.

25 11. A feed member for lubricant dispens-

ers comprising a tubular end portion and having an arcuate side adapted for engaging a wheel and lubricant collecting flanges laterally projecting from the said side.

12. A device of the class described comprising a lubricant dispenser, a mounting sleeve spaced therefrom and arranged parallel thereto, and through which a portion of the dispenser is longitudinally shiftably arranged and a feed spring for the dispenser 35 adjustably tensioned between the latter and the said sleeve.

13. A lubricant dispenser including a slidably resiliently mounted lubricant containing tube, and a feed tube rigidly connected 40 to said containing tube.

14. The combination with a lubricant dispenser including a lubricating tube, of a tension supporting means for said tube operatively arranged to cause the container to bodily slide longitudinally and swing in an 45 arcuate path.

In testimony whereof I affix my signature.

WILLIAM C. JOHNSON.
